UNITED STATES PATENT OFFICE.

CHARLES TREVOR, INCOMPETENT, OF JERSEY CITY, NEW JERSEY, BY JAMES F. RYAN,
GUARDIAN, OF JERSEY CITY, NEW JERSEY.

AEROPLANE.

Application filed January 23, 1929. Serial No. 334,566.

The present invention relates generally to aeroplanes and more particularly to means for controlling the aeroplane in its maneuvers in the air.

5 The prime object of the invention resides in the provision of an aeroplane having a tail structure hingedly mounted thereon so that it may be swung at an angle to the fuselage for assisting the aeroplane in coming out of 10 nose dives and further in assisting the aeroplane in climbing.

Another very important object of the invention resides in the provision of an aeroplane of this nature which includes a fuselage 15 having a hingedly mounted tail thereon in combination with means for swinging the tail in an angular position with respect to the fuselage.

A further very important object of the invention resides in the provision of an aeroplane of this nature including a fuselage with a hingedly mounted tail thereon, in combination with a pair of wings or fins mounted one to each side and above the normal position of the tail and supported by means of 25 arms rigidly attached to the fuselage.

A still further very important object of the invention resides in the provision of an aeroplane of this nature which is exceedingly 30 simple in its construction, strong and durable, easy to manipulate, and thoroughly efficient and reliable for the purposes intended.

With the above and numerous other objects in view as will appear as the description proceeds, the invention resides in certain novel features of construction, and in the combination and arrangement of parts as will be hereinafter more fully described and claimed.

In the drawing:

40 Figure 1 is a side elevation of an aeroplane embodying the features of my invention,

Figure 2 is a top plan view thereof,

Figure 3 is a longitudinal vertical section therethrough,

45 Figure 4 is a sectional view through the shock absorber,

Figure 5 is a sectional view through one of the auxiliary wings, and

50 Figure 6 is a fragmentary longitudinal vertical section through the tail showing a gondola therein.

Referring to the drawing in detail it will

be seen that the numeral 5 denotes a fuselage with a tail 6 hingedly mounted thereon as at 7. A bellows 8 is mounted with one end fixed to a cross bar 9 in the hinged end of the tail 6 and the other end fixed to a cross bar 10 in the rear end of the fuselage 5, so that when the bellows 8 is expanded the tail 6 will be swung to an angular position in relation to the fuselage as is indicated by dotted lines in Figure 3.

A valve 11 is disposed in a pipe 12 leading to the front end of the bellows 8 through the cross bar 10 and a plurality of branches 14 lead from a valve 11 forwardly to funnels 15 in the nose portion of the fuselage for the purpose of collecting air as the aeroplane is moving forwardly or as in a nose dive to expand the bellows 8 and swing the tail 6 to its 70 angular position in relation to the fuselage 5.

A bumper 16 of suitable construction is mounted on the top of the fuselage 5 adjacent the hinge joint 7 so that the tail may abut therewith when in its angular position. A 75 pivoted catch 18 in the rear of the fuselage 5 engages a projection 19 at the bottom of the forward end of the tail 6 to hold said tail in rigid alinement with the fuselage 5 under ordinary flying conditions.

This catch 18 is releasable by a cable 20 trained over pulleys 21 in the fuselage and controllable by a knob 22 or in any other preferred manner from the instrument board 23 of the front of the cockpit C in the fuselage 5. A bolt 24 is slidable in a bracket 25 and has teeth 26 normally interposed between teeth 27 on the forward edge of the tail 6 when said tail 6 is in alinement with the fuselage.

A pivotally mounted lever 28 in the fuselage is connected with the bolt 24 and holds the bolt in its normal position just referred to by means of a spring 29. A cable 30 is connected with the lever and with the cable 20 so that this latch bolt 24 may be simultaneously released with the catch 18 so as to permit the air pressure set up through funnels 15, pipe branches 14 and pipe 12 in the bellows 8 to swing the tail 6 by the expansion of the bellows.

A cable 33 connected with the valve 11 and when pulled by a knob 34 on the instrument board 23 this valve is opened to the atmosphere to allow the air to escape from the bel-

lows so that the bellows will contact because of the weight of the wing 6 thereby allowing the wing 6 to return to a position in alignment with the fuselage.

In order to prevent the tail 6 from swinging too suddenly to its angular position I provide checks one on each side of the rear end of the fuselage. Each check includes a tube 40 permanently closed at 41 at its bottom end and having a removable closure 42 at its top end. This tube is mounted longitudinally on a plate 43 which is fixed in any suitable manner as at 44 in a substantially vertical position on the fuselage 5.

The tube is longitudinally slotted as is indicated at 44. A block 45 is slidable in the tube and has an eyelet 46 projecting through the slot 44. A cable 47 is attached to the eyelet 46 and is trained over a pulley 48 journaled in a bracket 49 at the bottom end of the tube.

These cables 47 are anchored as at 50 on the forward end of the tail remotely from the hinged joint 7 and in order to swing the tail 25 to its angular position it is necessary to compress springs 51 in the tubes 40, these springs being interposed between the blocks 45 and the bottoms 41.

In order to properly stabilize the aeroplane 30 provided with my tail structure it is preferable to provide a pair of auxiliary wings 53 which are constructed with centrally located transverse bars 54 from which depend the vertical portions of L-shaped brackets 55. The front ends of the horizontal portions of 35 which are rigidly attached to the rear bottom portion of the fuselage 5 in any preferred manner.

These auxiliary wings 53 are braced by guy 40 wires 57 attached to collars 58 on the bracket 55. The vertical portions of these brackets 55 rise one to each side of the tail 6.

If desired a gondola 60 for passengers may be rockably mounted in the fuselage on a 45 shaft 61, said shaft 61 being disposed above the center of gravity of the gondola so that this gondola will maintain an upright position at all times in the tail regardless as to the position of the tail.

In the present embodiment of the invention 50 I have shown a bi-plane structure including an upper wing 63 and lower wing section 54. It is to be noted in Figure 1 that the auxiliary wings 53 are preferably located in substantially the same plane with the wing 63.

At the rear of the tail 6 there are provided elevators 65 and rudders 66 in the usual conventional manner.

With the parts positioned in normal flying 60 relationship to each other as is disclosed in Figures 1 and 3 it will be seen that the aviator may pull upon the knob 22 if the aeroplane should get into a nose dive thereby releasing the latch bolt 24 and the catch 18 so 65 that the rush of air into the funnels 15

through the branches 14, valve 11 and pipe 12 will expand the bellows 8 so as to swing the tail 6 to the dotted line position shown in Figure 3 and it will tend to bring the aeroplane out of the nose dive.

Of course the same manipulation may be used to obtain a quick ascent in ordinary air maneuvers.

It is thought that the construction, utility, operation and advantages of this invention 75 will now be quite apparent to those skilled in this art without a more detailed description thereof.

The present embodiment of the invention has been disclosed in detail merely for the 80 purposes of exemplification since in actual practice it attains the features of advantage enumerated as desirable in the statement of the invention and the above description. It will be apparent that changes in the details 85 of construction, and in the combination and arrangement of parts may be resorted to without departing from the spirit or scope of the invention, as hereinafter claimed or sacrificing any of its advantages.

Having thus described my invention, what I claim as new is:

1. An aeroplane of the class described including a fuselage, a tail, means hingedly mounting the forward upper portion of the 95 tail to the rear upper portion of the fuselage, and stabilizing means carried by the fuselage and disposed alongside the plane of movement of the tail.

2. An aeroplane of the class described including a fuselage, a tail, means hingedly mounting the forward upper portion of the tail to the rear upper portion of the fuselage, a bellows, means attaching one end of the bellows to the forward end of the tail, means attaching the other end of the bellows to the rear end of the fuselage, and means for expanding the bellows to cause the tail to swing to an angular position in respect to the fuselage.

3. An aeroplane of the class described including a fuselage, a tail, means hingedly mounting the forward upper portion of the tail to the rear upper portion of the fuselage, a bellows, means attaching one end of the bellows to the forward end of the tail, means attaching the other end of the bellows to the rear end of the fuselage, and means for expanding the bellows to cause the tail to swing to an angular position in respect to the fuselage, releasable means for locking the tail to the fuselage in alignment therewith.

4. An aeroplane of the class described including a fuselage, a tail, means hingedly mounting the forward upper portion of the 125 tail to the rear upper portion of the fuselage, a bellows, means attaching one end of the bellows to the forward end of the tail, means attaching the other end of the bellows to the rear end of the fuselage, and means for ex-

- 5 panding the bellows to cause the tail to swing to an angular position in respect to the fuselage, said means comprising a pipe leading to the front end of the bellows to the front 5 end of the fuselage.
- 5 6. An aeroplane of the class described including a fuselage, a tail, means hingedly mounting the forward upper portion of the tail to the rear upper portion of the fuselage, 10 a bellows, means attaching one end of the bellows to the forward end of the tail, means attaching the other end of the bellows to the rear end of the fuselage, and means for expanding the bellows to cause the tail to swing 15 to an angular position in respect to the fuselage, said means comprising a pipe leading to the front end of the bellows to the front end of the fuselage, one end of the pipe terminating in a funnel.
- 15 7. An aeroplane of the class described including a fuselage, a tail, means hingedly mounting the forward upper portion of the tail to the rear upper portion of the fuselage, a bellows, means attaching one end of the bellows to the forward end of the tail, means 20 attaching the other end of the bellows to the rear end of the fuselage, and means for expanding the bellows to cause the tail to swing to an angular position in respect to the fuselage, said means comprising a pipe leading to the front end of the bellows to the front end of the fuselage, a bumper on the upper portion of the rear end of the fuselage.
- 25 8. An aeroplane of the class described including a fuselage, a tail, means hingedly mounting the forward upper portion of the tail to the rear upper portion of the fuselage, a bellows, means attaching one end of the bellows to the forward end of the tail, means 30 attaching the other end of the bellows to the rear end of the fuselage, and means for expanding the bellows to cause the tail to swing to an angular position in respect to the fuselage, said means comprising a pipe leading to the front end of the bellows to the front end of the fuselage, a bumper on the upper portion of the rear end of the fuselage.
- 35 9. An aeroplane of the class described including a fuselage, a tail, means hingedly mounting the forward upper portion of the tail to the rear upper portion of the fuselage, a bellows, means attaching one end of the bellows to the forward end of the tail, means 40 attaching the other end of the bellows to the rear end of the fuselage, and means for expanding the bellows to cause the tail to swing to an angular position in respect to the fuselage, said means comprising a pipe leading to the front end of the bellows to the front end of the fuselage, one end of the pipe terminating in a funnel, a bumper on the upper portion of the rear end of the fuselage, a pair 45 of L-shaped arms rigidly attached to the fuselage and extending one to each side of the tail and vertical arms rising alongside thereof, and wings on the upper ends of the brackets.
- 45 10. An aeroplane of the class described including a fuselage, a tail, means hingedly mounting the forward upper portion of the tail to the rear upper portion of the fuselage, a bellows, means attaching one end of the bellows to the forward end of the tail, means 50 attaching the other end of the bellows to the rear end of the fuselage, and means for expanding the bellows to cause the tail to swing to an angular position in respect to the fuselage, sleeves mounted on the outside of the rear ends of the fuselage, blocks in the sleeve, 55 springs urging the blocks upwardly in the sleeves, cables attached to the blocks, pulleys over which the cables are trained, said cables being anchored to the lower front portions of the tail.
- 55 11. An aeroplane of the class described including a fuselage, a tail, means hingedly mounting the forward upper portion of the tail to the rear upper portion of the fuselage, a bellows, means attaching one end of the bellows to the forward end of the tail, means 60 attaching the other end of the bellows to the rear end of the fuselage, and means for expanding the bellows to cause the tail to swing to an angular position in respect to the fuselage, sleeves mounted on the outside of the rear ends of the fuselage, blocks in the sleeve, 65 springs urging the blocks upwardly in the sleeves, cables attached to the blocks, pulleys over which the cables are trained, said cables being anchored to the lower front portions of the tail.
- 65 12. An aeroplane of the class described including a fuselage, a tail, means hingedly mounting the forward upper portion of the tail to the rear upper portion of the fuselage, a bellows, means attaching one end of the bellows to the forward end of the tail, means 70 attaching the other end of the bellows to the rear end of the fuselage, and means for expanding the bellows to cause the tail to swing to an angular position in respect to the fuselage, a wing on the fuselage, and a pair of auxiliary wings one to each side of the tail structure in substantially the same plane with the first mentioned wing.
- 70 13. An aeroplane of the class described including a fuselage, a tail, means hingedly mounting the forward upper portion of the tail to the rear upper portion of the fuselage, a bellows, means attaching one end of the bellows to the forward end of the tail, means 75 attaching the other end of the bellows to the rear end of the fuselage, and means for expanding the bellows to cause the tail to swing to an angular position in respect to the fuselage, a wing on the fuselage, and a pair of auxiliary wings one to each side of the tail structure in substantially the same plane with the first mentioned wing.
- 75 14. An aeroplane of the class described including a fuselage, a tail, means hingedly mounting the forward upper portion of the tail to the rear upper portion of the fuselage, a bellows, means attaching one end of the bellows to the forward end of the tail, means 80 attaching the other end of the bellows to the rear end of the fuselage, and means for expanding the bellows to cause the tail to swing to an angular position in respect to the fuselage, a wing on the fuselage, and a pair of auxiliary wings one to each side of the tail structure in substantially the same plane with the first mentioned wing.
- 80 15. An aeroplane of the class described including a fuselage, a tail, means hingedly mounting the forward upper portion of the tail to the rear upper portion of the fuselage, a bellows, means attaching one end of the bellows to the forward end of the tail, means 85 attaching the other end of the bellows to the rear end of the fuselage, and means for expanding the bellows to cause the tail to swing to an angular position in respect to the fuselage, a wing on the fuselage, and a pair of auxiliary wings one to each side of the tail structure in substantially the same plane with the first mentioned wing.
- 85 16. An aeroplane of the class described including a fuselage, a tail, means hingedly mounting the forward upper portion of the tail to the rear upper portion of the fuselage, a bellows, means attaching one end of the bellows to the forward end of the tail, means 90 attaching the other end of the bellows to the rear end of the fuselage, and means for expanding the bellows to cause the tail to swing to an angular position in respect to the fuselage, a wing on the fuselage, and a pair of auxiliary wings one to each side of the tail structure in substantially the same plane with the first mentioned wing.
- 90 17. An aeroplane of the class described including a fuselage, a tail, means hingedly mounting the forward upper portion of the tail to the rear upper portion of the fuselage, a bellows, means attaching one end of the bellows to the forward end of the tail, means 95 attaching the other end of the bellows to the rear end of the fuselage, and means for expanding the bellows to cause the tail to swing to an angular position in respect to the fuselage, a wing on the fuselage, and a pair of auxiliary wings one to each side of the tail structure in substantially the same plane with the first mentioned wing.

In testimony whereof, I affix my signature.
 JAMES F. RYAN,
Guardian of Charles Trevor, Incompetent.
